United States Patent Office

Des. 227,613
Patented July 3, 1973

227,613

CARRYING CASE

Sergio Montanari, Via Leopoldo Nobili 11,
Rome, Italy

Filed July 27, 1971, Ser. No. 166,657

Claims priority, application Italy Jan. 29, 1971

Term of patent 14 years

Int. Cl. D3—01

U.S. Cl. D87—1 R

Fig. 2.

Fig. 5.

Fig. 3.Fig. 4.Fig. 5.FIG. 1 is a front elevational view of a carrying case showing my new design;

FIG. 2 is a side elevational view;

FIG. 3 is a top plan view;

FIG. 4 is a bottom plan view;

FIG. 5 is a top perspective view; and

FIG. 6 is a fragmentary sectional view on line 6—6 of FIG. 1.

The side opposite that shown in FIG. 1 is substantially a mirror image thereof.

I claim:

The ornamental design for a carrying case, substantially as shown and described.
